WILLIAM KURTZ, OF NEW YORK, N. Y.

Letters Patent No. 104,963, dated July 5, 1870.

PHOTOGRAPHIC REFLECTOR.

The Schedule referred to in these Letters Patent and making part of the same.

To all whom it may concern:

Be it known that I, WILLIAM KURTZ, of the city of New York, in the county and State of New York, have invented a new and Improved Photographic Reflector; and I do hereby declare that the following is a full, clear, and exact description thereof, which will enable others skilled in the art to make and use the same, reference being had to the accompanying drawing forming part of this specification.

Figure 1 represents a front elevation of my improved photographic reflector.

Figure 2 is a horizontal section of the same.

Figures 3, 4, and 5 are diagrams, illustrating the use of my reflector.

Similar letters of reference indicate corresponding parts.

This invention has for its object to construct an adjustable shield, by means of which the light thrown upon articles that are photographed can be absolutely controlled at pleasure.

The screens heretofore employed are on upright, jointed frames, which can only very imperfectly regulate the degree of shade.

My invention consists in the use of a jointed screen, with suitable concave shields, which can be set at any suitable degree of inclination, for the purpose of regulating the light thrown upon the article or person to be photographed.

A, in the drawing, represents an upright frame of oblong or other suitable shape, supported on legs B B, so as to stand firm wherever it may be placed. The frame is composed of two upright bars, *a a*, and of a top cross-piece, *b*. To the inner side of each bar *a* is hinged a plate, *C*, and to the under side of the cross-piece *b* is also hinged a similar cross-plate, *D*. These three parts constitute an inner frame, of which each part may be set at any suitable angle to the main frame A.

The lower end of this adjustable frame C D may be formed by a pivoted plate, *E*, as shown; but this can be readily dispensed with.

To the outer side of each post *a* is hinged a vertical bar, *d*, and to each bar *d* is, by a pin, *e*, swiveled a concave shield, *F*. The two shields *F* can, on and with the bars *d*, be swung in any desired position to throw the desired shade.

The frame A is to be placed between the object and the camera, so that the rays of light pass through the opening in the frame.

It is evident that the adjustable shields or reflectors employed on the frame can be conveniently set to produce the desired effect. They can be made of suitable material, and colored to produce the desired reflex.

An effect not quite as powerful as that produced by all the shields can be obtained by using the outer shields *F* only. I do not, therefore, necessarily confine myself to their combination with the inner shields B C D E.

Heretofore photographers were required to place their sitters with their faces turned fully or in part to the light, owing to the impossibility of photographing that part of the face and drapery which was turned from the light. Every attempt to obtain a good photograph from unlighted positions resulted in deep opaque shadows, entirely devoid of detail, while the high light on the other side was too intense. A proper modulation of light, shade, and detail was thus hardly attained, the picture being full of harsh and severe contrasts.

By the aid of my invention the light can be managed and controlled at pleasure.

Thus, if G, fig. 3, represents a circular block, illuminated by rays of light from the side, and H the camera, the simple act of photographing would produce an intense light at *f* and a deep shadow at *g*, without proper modulation. By adding the ordinary reflector *h*, as in fig. 4, the effect would be to drive the shadow away from *g* toward *f*, and to thereby illuminate strongly the extreme end, at *g*.

The mode of applying the shadow is absurd, and entirely inartistic. By adding my improved counter-reflector the result will be as indicated in fig. 5. The rays of light striking on the wing *F* drive away a portion of the deep shadow, which is, however, prevented from dwelling on the center of the block, as the same is illuminated by reflections from the wing *F*. The block now assumes its natural appearance, and is so lighted by the counter-reflector that it can be photographed with the proper light, which could heretofore, not be done.

Having thus described my invention, I claim as new and desire to secure by Letters Patent—

1. The improved counter-reflector herein described.
2. The photographic reflector, consisting of the open frame A and the inner shields C D E, all arranged as set forth.
3. The combination of the swiveled shields F F with the open frame A, substantially as and for the purposes herein shown and described.

W. KURTZ.
